Primary Examiner—Nelson C. Holtje*Assistant Examiner*—Janice E. Seeger*Attorney, Agent, or Firm*—Norman B. Rainer[57] **CLAIM**

The ornamental design for an enclosed hammock, as shown and described.

DESCRIPTION

FIG. 1 is a side elevational view of an enclosed hammock, showing my new design, the opposite side being identical thereto;

FIG. 2 is an end elevational view, the opposite end being identical thereof; and,

FIG. 3 is a top plan view thereof.

The netting pattern shown is continuous throughout.

FIG. 1

FIG. 2

FIG. 3
